UNITED STATES PATENT OFFICE.

JAMES C. HICKEY AND OLIVER J. CANTRELLE, OF NEW ORLEANS, LOUISIANA.

TRUCK.

1,297,164.

Specification of Letters Patent. Patented Mar. 11, 1919.

Application filed September 17, 1918. Serial No. 254,477.

To all whom it may concern:

Be it known that we, JAMES C. HICKEY and OLIVER J. CANTRELLE, citizens of the United States, and residents of New Orleans, in the parish of Orleans and State of Louisiana, have invented certain new and useful Improvements in Trucks, of which the following is a specification.

Our invention is an improvement in trucks, and has for its object to provide mechanism for use in connection with the usual freight truck, either hand or motor operated, for depositing and stacking the load automatically.

15 In the drawings:

Figure 1 is a front view of the improved truck; and

Fig. 2 is a side view.

The present embodiment of the invention 20 is shown in connection with a truck consisting of a body 1 and the usual wheels 2, connected to the body by the bolsters 3, and the improvement comprises a pair of handle members 4 connected by cross plates 5, the 25 lower ends of the handle members being curved forwardly at an obtuse angle to the body, as indicated at 6, to provide a support for the articles to be stacked, as, for instance, material in bags.

30 As is known, much time is required in transporting packaged stuff, as, for instance, grain in bags, where it is essential to handle the same piece by piece both in loading and unloading. With the present invention the 35 necessity for handling the bags or packages separately in unloading is eliminated. The bags are supported by the portions 6 of the handle members, upon plates 7 which are arranged upon the portions 6. Angle plates 40 8 are secured to the sides of the portions 6, each angle plate having two portions in substantial alinement with the portions 4 and 6 of the handle members.

45 Wheels 9 are secured to an axle 10 which is journaled in the depending portions of the plates 8, each wheel being journaled in a stirrup formed by the depending portion of the plate, and a plate 11 secured to the outer face of the depending portion in the 50 manner shown in Fig. 1. The handle portions 4 of the truck are secured to levers 12, each lever having at its forward end an angular portion 13 to which the handle member is secured, and the levers are se-

cured to a shaft 14 which is journaled in standards 16 on the body 1 of the main truck. Each of these levers has at its rear end a downwardly offset portion 17, and a link 18 connects each of these portions 17 with a substantially U-shaped bracket 19 secured to the adjacent handle member near its upper end. Thus when the levers are swung upon the standard 16 the elements 4, 5 and 18 will swing therewith, taking the dotted line position of Fig. 2, wherein the 65 wheels 9 contact with the supporting surface for the truck.

A counterweight 20 is mounted upon each lever, for normally balancing the attachment to hold it in the full line position of 70 Fig. 2, and the levers are prevented from swinging when the attachment is loaded by means of a dog 21 arranged adjacent to one lever and pivoted to a lug 22 on the body of the truck. A latch lever 23 is also pivoted to this lug, and the forwardly up curled end of the latch lever engages the dog to lift the same when the rear end of the latch lever is depressed.

Referring to Fig. 2, it will be noticed that 80 the curve of the latch lever engages a curved portion of the latch, to prevent the latch swinging when the latch lever is in the normal position of Fig. 2. The latch lever is operated by means of a lever 24 85 which is pivoted to a bracket 25 on the truck body and the lever is connected to the latch lever by a link 26. To release the latch, it is only necessary to swing the lever 24 rearwardly. This lifts the latch and releases the truck attachment so that it can swing into the dotted line position of Fig. 2. A guard 27 is provided for the lever 24, the guard being secured to the truck body, as shown. 90

In operation, when the bags or other packaged goods are loaded in superposed relation upon the plates 7, with the parts in the full line position of Fig. 2, the attachment will be held in such position under 100 the weight of the material by the latch 21. When it is desired to dump the load, the lever 24 is moved rearwardly, causing the latch 21 to release the levers 12. By means of the grips on the handle members 4 the 105 parts are now moved into the dotted line position of Fig. 2, thus dumping the stack of packaged goods in a stack. The im- 95

proved attachment may be applied to any existing truck, whether hand operated or power operated.

We claim:

- 5 1. In combination with a truck, of an attachment comprising a pair of laterally spaced rigidly connected handle members, each having at the lower end a portion extending at an obtuse angle to the body of the handle member, depending lugs at the connection of the body portions with the laterally bent portions, a wheel journaled in each lug, levers pivoted to the truck and rigidly connected at their outer ends to the handle members near the laterally bent portions, a rigid connection between the other end of each handle member and the adjacent lever, a latch for normally preventing swinging of the lever, and means for releasing the latch. 35
- 10 2. In combination with a truck, of an attachment comprising spaced rigidly connected handle members having angular portions at the lower ends for supporting a pile of packaged material, levers pivoted to the truck and connected to the handle members, a latch for preventing swinging movement of the levers and manually operated means for releasing the latch, and a counterweight adjustable on the levers for balancing the attachment. 40
- 15 3. In combination with a truck, of an attachment comprising spaced rigidly connected handle members having angular portions at the lower ends for supporting a pile of packaged material, levers pivoted to the truck and connected to the handle members, a latch for preventing swinging movement of the levers and manually operated means for releasing the latch, and a counterweight adjustable on the levers for balancing the attachment. 45
- 20 4. In combination with a truck, of an attachment comprising spaced rigidly connected handle members having angular portions at the lower ends for supporting a pile of packaged material, levers pivoted to the truck and connected to the handle members, and a latch for preventing swinging movement of the levers and manually operated means for releasing the latch. 50
- 25 5. In combination with a truck, of an attachment comprising a pair of laterally spaced rigidly connected handle members, each having at the lower end a portion extending at an obtuse angle to the body of the handle member, depending legs at the connection of the body portions with the laterally bent portions, a wheel journaled in each leg, levers pivoted to the truck and rigidly connected at their outer ends to the handle members near the laterally bent portions, a rigid connection between the other end of each handle member and the adjacent lever, a latch for normally preventing swinging of the lever, and means for releasing the latch. 55
